UNITED STATES PATENT OFFICE.

JAMES ED McLAUGHLIN AND DONAT BORDELEAU, OF GRAND MERE, QUEBEC, CANADA.

SEAL-LOCK FOR FREIGHT-CAR DOORS.

1,244,625.

Specification of Letters Patent.

Patented Oct. 30, 1917.

Application filed September 16, 1915. Serial No. 51,115.

To all whom it may concern:

Be it known that we, JAMES E. McLAUGHLIN and DONAT BORDELEAU, subjects of the King of England, residing at Grand Mere, 5 in the Province of Quebec, Dominion of Canada, have invented certain new and useful Improvements in Seal-Locks for Freight-Car Doors; and they do hereby declare the following to be a full, clear, and exact description of the invention, such as will enable others skilled in the art to which it 10 pertains to make and use the same.

This invention relates to new and useful improvements in seal locks for freight car 15 doors.

An object of the invention resides in the provision of a lock which will be easily operable and which consists, essentially, of a bolt and socket, which bolt will swing to a 20 position where it will permit the locking hasp to be readily disengaged and which will move automatically to a position in alinement with the socket member so that it may be thrust therein conveniently.

With this and other objects in view, such 25 as will appear as our description progresses, our invention comprises the combination and arrangement of parts as set forth in and falling within the scope of the appended 30 claims.

In the drawing:

Figure 1 is a front elevation of the device showing the same in its locking position with a hasp and seal in place thereon;

35 Fig. 2 is a side elevation thereof;

Fig. 3 is a similar view with the bolt withdrawn from the socket;

Fig. 4 is a vertical sectional view on line 4-4 of Fig. 1;

40 Fig. 5 is a similar view with the parts in the positions shown in Fig. 3 of the drawing, and

Fig. 6 is a transverse sectional view on line 6-6 of Fig. 1.

45 Referring to the drawing by reference characters wherein like parts are indicated by like characters throughout the several views:

The invention as illustrated in the drawing 50 includes a bracket 1 on which a pair of ears 2 and 3 are formed, the said ears being located adjacent the ends of the bracket. The upper ear is provided with a socket 4 for a purpose which will later appear.

55 Formed integral with the lower ear 3 are flanges 5. Slidably mounted in a rectangu-

lar opening 6 in the lower ear 3 is a bar 7 on the lower end of which a finger piece 8 is formed which is adapted to contact with the said ear 3 and limit the upward movement 60 of the bar. Pivots secured to the upper end of this bar 7 is a locking bolt which includes a body portion 9 and a bolt portion 10. Extending from the body portion 9 is a pair of spaced fingers 11 which are provided with toe portions 12. The bracket 1 is provided with a pair of spaced openings 13 adjacent the ear 3 through which the toe portions 12 of the fingers 11 are adapted to extend. Formed on the bracket 1 between 70 the ears 2 and 3 is a guide member 14 on which the body portion of the locking bolt is adapted to rest.

From this construction it will be seen that when the bolt portion 10 is withdrawn from 75 the socket 4 in the ear 2, the fingers 11 will ride along the bracket 1 until the toe portions 12 strike the upper face of the ear 3 at which time they will ride upon this face and because of the peculiar formation of the 80 said fingers 11, the locking bolt will be moved upon its pivot to a position such as shown in Fig. 3 of the drawing, at which time the hasp 15 may be withdrawn from the ear 2. Now as the bar 7 is pushed up- 85 wardly by means of the finger piece 8, the fingers 11 of the locking bolt will again ride upon the bracket 1 and the said bolt will be swung about its pivot until the body portion thereof engages the guide member 14, 90 which guide member will arrest the pivotal movement but will allow the locking bolt to have further sliding movement. This guide member 14 will arrest the locking bolt so that the bolt portion 10 thereof will aline 95 with the socket member 4 and so that the said bolt portion will penetrate the socket. This bolt portion is provided with a slot 16 through which a suitable seal 17 may be engaged.

100 It will thus be seen that we have provided a seal lock, the locking bolt of which is pivotally mounted so that it will aline automatically with the socket in which it is engageable and so that it will swing to such a 105 position that the hasp may be readily disengaged from the ear with which it engages.

While we have illustrated and described a particular embodiment of our invention, it has merely been for the sake of convenience 110 and we do not wish to be limited to that particular embodiment, as it is obvious that nu-

merous changes may be made in the details of construction without departing from the spirit of the invention or exceeding the scope of the appended claims.

5. What we claim is:—

1. In a seal lock, the combination with a bracket including an ear provided with a socket, of a slidably and pivotally mounted locking bolt having a portion adapted to engage in said socket, the said bolt being constructed and arranged to move pivotally upon its withdrawal from the socket and to align with the socket when moved in a direction toward the same and means for operating said bolt.
2. In a seal lock, the combination with a bracket including an ear provided with a socket, of a locking bolt slidably and pivotally mounted, the said bolt being constructed and arranged to move out of alignment with the socket when withdrawn therefrom.

Copies of this patent may be obtained for five cents each, by addressing the "Commissioner of Patents, Washington, D. C."

and to move into alignment, automatically, when moved toward the same.

3. In a seal lock, the combination with a bracket having a pair of spaced ears, one of said ears having a socket therein and the other of said ears having a rectangular opening, of a bar slidably mounted in said opening, a locking bolt pivotally mounted on the said bar and having means thereon adapted to coöperate with the ear in which the opening is formed so that it will swing out of alignment with the socket when withdrawn therefrom.

In testimony whereof, we affix our signatures, in the presence of two witnesses.

JAMES ED McLAUGHLIN.
DONAT BORDELEAU.
